[57] CLAIM

The ornamental design for a combined point of sale terminal and cash drawer, as shown and described.

DESCRIPTION

FIG. 1 is a front elevational view of a combined point of sale terminal and cash drawer showing my new design;

FIG. 2 is a rear elevational view thereof;

FIG. 3 is a right side elevational view thereof;

FIG. 4 is a left side elevational view thereof;

FIG. 5 is a top, plan view thereof;

FIG. 6 is a bottom plan view thereof;

FIG. 7 is a front elevational view of the point of sale terminal only;

FIG. 8 is a rear elevational view of FIG. 7;

FIG. 9 is a right side elevational view of FIG. 7;

FIG. 10 is a left side elevational view of FIG. 7;

FIG. 11 is a bottom plan view of FIG. 7;

FIG. 12 is a front elevational view of the cash drawer only;

FIG. 13 is a rear elevational view of FIG. 12;

FIG. 14 is a right side elevational view of FIG. 12;

FIG. 15 is a left side elevational view of FIG. 12; and

FIG. 16 is a top plan view of FIG. 12.
